UNITED STATES PATENT OFFICE

2,408,739

WINDOW CONSTRUCTION

Rodney Dawes, Royal Oak, Mich.

Application November 3, 1943, Serial No. 509,001

20 Claims. (Cl. 160—188)

1

This invention relates to window constructions, and more particularly to the type embodying a plurality of sashes adapted to vertical adjustments within the window frame, as well as outward tilting movement therein.

It is the object of the present invention to provide a two sash window centrally hinged and adapted to outward swinging movement on opening movement of either or both sashes.

It is the object of this invention to provide a double hinged window construction with manually operable window regulating means adapted to cause upward movement of the lower hinged sash throughout the entire length of the window opening, with the upper portion merely pivoting outwardly, whereby the two sash members are brought into parallel horizontal relationship at the top of the window frame.

It is the further object to provide a window construction with means permitting dropping of the upper sash pivotal support throughout the entire length of the window frame until the two sashes have assumed a parallel horizontal position at the bottom of the window frame, and with their common hinge being outwardly projected therefrom.

It is the further object herein to provide manually operable means for causing upward translation of the two parallel folded horizontal sashes from the bottom of the frame to the top thereof, or from the top thereof to the bottom.

It is the further object of this invention to arrange the weatherstripping of the intermediate hinged portions of the two sashes as well as at the bottom of the lower sash whereby on nominal releasing movement of the manual regulating means said central hinged portion will initially snap outwardly sufficiently to prevent binding of the window sashes upon further manual regulation.

It is the further object herein to provide manual regulating means for causing raising and lowering of the pivotal bottom support of the lower sash, as well as separately operable manual regulating means causing lowering and raising of the top pivotal support of the upper sash; it being understood that the central hinged portion of the window is at all times adapted to outward translation upon movement of either or both of said sashes.

It is the still further object herein to provide a window frame construction with vertical slotted sections for housing threaded rotatable window adjusting means, together with correspondingly threaded cooperating support and guide means

2

slidably disposed through said slotted portions and pivotally joined to the lower portions of the lower window sash, whereby on rotation of said adjusting means, said window support may be raised or lowered. At the same time the upper supports for the upper window sash pivoted thereto are slidingly and guidingly disposed through the slotted portions of said vertical sections.

It is the further object herein to provide a right handed thread at the lower ends of the window adjusting means, and left handed threads at the upper end portions of said means whereby the upper and lower portions of the two windows are adapted for vertical adjustment towards and away from each other.

It is the still further object herein to provide a similar construction employing a hollow threaded tube construction separately operable for causing elevation and lowering of the lower sash, and a secondary separately rotatable threaded shaft disposed through said hollow shaft for causing separate lowering and raising of the upper sash.

These and other objects will be seen in the following specification and claims wherein the present invention is seen to reside in the various combinations of elements and arrangements thereof, as illustrated in the accompanying drawings of which:

Fig. 1 is a partially sectioned side elevational view of the window construction.

Fig. 2 is a side elevational view of the same closed.

Fig. 3 is a partially broken away front elevational view of the window regulating means.

Fig. 4 is a fragmentary sectional view thereof on line 4—4 of Fig. 2.

Fig. 5 is an enlarged fragmentary section on line 5—5 of Fig. 1.

Fig. 6 is a partially sectioned front elevational view of a slightly different type of window construction.

Fig. 7 is a fragmentary side elevational section of the upper window adjustable support shown in Fig. 6.

It will be understood that the above drawings are merely illustrations of preferable embodiments of the present invention and that other embodiments are contemplated within the scope of the invention as set out in the appended claims.

Referring to the drawings Figs. 1, 2 and 3 show the hollow rectangular frame 1 with the longitudinal sill 2 provided intermediate the ends

thereof but adjacent the lower end. Lower sash 3 with pane 4 is hinged at 5 to the upper sash 6 containing window glass 7.

Hollow channel members 8 and 9 longitudinally slotted at 10 throughout their length are provided within frame 1 as shown in Fig. 4, being nested and suitably secured against the vertical members of frame 1, with said slotted portions facing the outside of the frame.

As shown in Figs. 1 through 4 shafts 11 and 12 respectively threaded at 13 and 14 and provisioned centrally within channel members 8 and 9 are suitably supported therein, having annular collars 15 at their lower ends for rotatable support upon bearings 16 within sill 2. The upper ends of vertical shafts 11 and 12 are rotatably journaled within bearings 17 in the top member of frame 1.

Bevel gears 18 and 19 keyed on the lower ends of shafts 11 and 12 are in operative mesh with the two bevel gears 20 and 21 keyed on opposite ends of horizontal shaft 22 which is rotatably supported by the two brackets 23 and 24 depending below sill 2.

As shown in Figs. 1 and 2 brackets 25 and 26 depending centrally below sill 2 provide a journal and support for the manually rotatable window regulator 27 with shaft 28. Worm gear 29 keyed on shaft 28 operatively and threadably meshes with gear 30 keyed on horizontal shaft 22, whereby rotation of regulator 27 will cause rotation of shaft 22 and rotation of shafts 11 and 12 geared thereto.

Dogs 31 and 32 shown in Figs. 1 and 3 pivotally hinged at 33 within notches 34 in the bottom of sash 3 are in threaded engagement at 35 and 36 with the respective vertical rotatable shafts 11 and 12 and their threaded portions 13 and 14.

On the other hand dogs 37 and 38 shown in Figs. 1, 2 and 5 pivotally hinged at 39 at the top edge of upper sash 6 have laterally flanged guide portions 40 on the ends thereof for cooperative sliding engagement against the inner surface of channel members 8 and 9 within frame 1.

Guides 40 are normally retained slightly below their extreme upper position by the transverse pins 41 slidable through frame 1 and channel members 8 and 9. Pins 41 with handles 42 have annular collars 43 engaged by coiled springs 44 within spring housings 45 which spring tends to resist withdrawing of said pins partially from frame 1 but allows sufficient withdrawal to permit dogs 37 and 38 to be free to drop within channel members 8 and 9.

Thus a sliding pivotal support is provided for the upper part of sash 6, which is adapted for guided sliding vertical adjustment through dogs 37 and 38 within slotted channels 8 and 9. With the amount of friction previously ascertained between flanged portions 40 of dogs 37 and 38 and slotted channels 8 and 9 it is possible to effect downward movement of sash 6 when released merely by applying a minimum of force and permitting gravity to do the rest.

With sashes 3 and 6 pivotally centrally at 5 manual rotation of regulator 27 in one direction effecting rotation of shafts 11 and 12 will cause dogs 31 and 32 to ride upwardly upon their threaded connections so that the lower ends of sash 3 will travel upwardly while the hinged portions 5 of both sashes 3 and 6 will progressively project outwardly.

By continual rotation of handle 27 it is possible to cause sash 3 to ride up the full height of window frame 1, with the result that both sashes 3

and 6 will be in horizontal and in parallel relation at the top of the frame. By rotating handle 27 in the opposite direction it is seen that both sashes will be closed to the position shown in Fig. 2.

However at elevated horizontal position of both sashes at the top of frame 1, pins 41 may be manually withdrawn sufficiently against springs 44 to release the upper pivotal supports of sash 6, whereby upon opposite rotation of handle 27 sash 3 is operatively lowered in horizontal position, with upper sash 6 horizontally resting thereon and also riding downwardly. Thus both sashes may be brought down while remaining in horizontal parallel relation to the sill 2 near the bottom of frame 1. In this position the outside surface of glass 7 of upper sash 6 may be easily washed. While in the extreme upward horizontal positions or intermediate horizontal positions of sashes 3 and 6 the outside of glass 4 in the lower sash can be easily washed.

It is contemplated that lower dog attachments 35 and 36 may have projections 35' as in Fig. 2 for operative engagement with the ends of pins 41 angularly shaped at 41', for causing releasing movement to the right on engagement therewith, at the same time permitting release of upper dog guides 40, permitting downward movement thereof.

Without actuation of handle 27 upper sash 6 may be lowered merely by manually releasing pins 41 permitting dogs 37 and 38 to guidingly slide downwardly to any intermediate position along window frame 1. It is seen that any downward movement of sash 6 causes at least outward movement of the hinged portion 5 of the two sashes, even though the lower portion of the lower sash remains stationary.

Weatherstripping 46 and 47 is provided upon the bottom edges respectively of sashes 6 and 3, and are so provided that a slight releasing movement of handle 27 will permit the central hinged portion 5 to snap outwardly sufficiently to prevent any binding of the sashes against each other upon further actuation of handle 27. By this "pop out" action it is clear that any of the adjustments of the sashes above described are possible without any binding.

In fully closed position of the window as in Fig. 2, upper sash 6 rests upon lower sash 3. However in the initial "pop out" position above, upper dog members 38 and 39 drop down slightly to rest upon pins 41.

While the above description shows means releasing the upper sash to be free falling subject to a certain amount of desired sliding friction, it is contemplated that dogs 37 and 38 may be in threaded engagement with corresponding threaded portions oppositely threaded in direction from threaded portions 13 and 14, as shown in Fig. 7. Thus on rotation of regulator 27 in one direction, dogs 37 and 38 on sash 6 and dogs 31 and 32 on sash 3 would approach each other with the result that both sashes would be in horizontal parallel positions at the center of the frame opening. Rotation of regulator 27 in the opposite direction would cause dogs 37 and 38, and 31 and 32 to move in threaded engagement with shafts 11 and 12, but away from each other to intermediate positions or to the closed position of Fig. 2.

It is contemplated however that it may be desirable to open sashes 3 and 6 in unequal amounts, and to accomplish this a slightly different construction is shown in Figs. 6 and 7. Within the hollow channel sections 8 and 9

slotted at 10 are provided the hollow threaded rotatable shafts 48 and 49, threadably engaged by the interiorly threaded portions 50 and 51 of corresponding dogs 52 and 53. Said dogs 52 and 53 slidably project through slots 10 and are adapted for pivotal attachment to the lower end of the lower window sash 3 in the manner illustrated in Fig. 1.

Shafts 48 and 49 rotatably carried and journaled by bearings 54 in sill 2 have bevel gears 55 and 56 on their ends in operative engagement with bevel gears 57 and 58 on the ends of rotatable shaft 59. Shaft 59 journaled by brackets 60 and 61 depending below sill 2 carries gear 62 in mesh with rotatable spiral gear 63. The latter is rotatably carried by manually rotatable shaft 64 and a suitable handle, not shown, supported by bracket 65; or a pair of such brackets 60 and 61 depending from sill 2 in a manner similar to brackets 25 and 26 shown in Fig. 1.

Thus rotation of regulator shaft 64 causes rotation of horizontal bar 59 and vertical hollow threaded shafts 48 and 49, effecting vertical adjustments of the corresponding dogs 52 and 53 secured to the lower window sash. Raising and lowering of the lower sash is thus accomplished by manual rotation of regulator shaft 64.

Within hollow threaded shafts 48 and 49 are rotatably disposed the oppositely threaded shafts 65' and 66 journaled at 67 within the top portion 30 of frame 4 and with their annular collar portions 68 at the lower end providing a supporting journal with respect to brackets 69 secured to frame 4, below sill 2.

Rotatable shafts 65' and 66 have bevel gears 35 70 and 71 adjacent their ends in mesh with corresponding bevel gears 72 and 73 on shaft 74, also rotatably journaled through the supporting brackets 60 and 61 below sill 2.

Shaft 74 carries gear 75 in mesh with rotatable spiral gear 76 on rotatable regulator shaft 40 77 journaled and supported by bracket 78 or a pair of such brackets similar to the brackets 25 and 26 shown in Fig. 1.

Thus rotation of regulator shaft 77 causes rotation of bar 74 and vertical threaded shafts 65' and 66, effecting vertical adjustments of the corresponding threaded portions 79 and 80 on dogs 81 and 82.

Dogs 81 and 82 slidably projecting through slots 10 in hollow sections 8 and 9 pivotally support at 83 the upper portions of upper sash 6 as shown in Fig. 7. Thus vertical adjustments of upper sash 6 are effected by regulator shaft 77 independently of the vertical adjustments of lower sash 3 through its regulator shaft 64. It is contemplated however that both sashes 3 and 6 are similarly hinged centrally and that said hinged portion projects outwardly upon the vertical adjustment of either or both of sashes 3 and 6.

It will be understood that the invention above described is also adaptable to door constructions wherein the door consists of two or more panels centrally hinged, together with means for causing vertical adjustments thereof.

Having described my invention reference should be had to the claims which follow for determining the scope thereof.

I claim:

1. A window construction comprising a rectangular frame having a single sash guideway, aligned lower and upper sashes pivotally joined by an intermediate hinge, pivotal means supporting the upper sash within said frame, aligned

pivotal means supporting the lower sash within said frame, and rotatable means vertically disposed and journaled within said frame operatively engaged by said lower sash pivotal means for vertical adjustments.

2. A window construction comprising a rectangular frame having a single sash guideway, aligned lower and upper sashes intermediately hinged together, pivotal means supporting said upper sash within said frame, aligned pivotal vertically adjustable means supporting the lower sash within said frame, and rotatable means vertically disposed and journaled within said frame operatively engaged by said lower sash pivotal means for vertical adjustments.

3. A window construction comprising a rectangular frame having a single sash guideway, aligned lower and upper sashes intermediately hinged together, pivotal means supporting the upper end of said upper sash within said frame, aligned pivotal vertically adjustable means supporting the lower end of said lower sash within said frame, and rotatable means vertically disposed and journaled within said frame operatively engaged by said lower sash pivotal means for vertical adjustments.

4. A window construction comprising a rectangular frame having a single sash guideway, aligned lower and upper sashes intermediately hinged together, pivotal vertically adjustable means supporting the upper sash within said frame, aligned pivotal vertically adjustable means supporting the lower sash within said frame, and rotatable means vertically disposed and journaled within said frame operatively engaged by said lower sash pivotal means for vertical adjustments.

5. A window construction comprising a rectangular frame having a single sash guideway, aligned lower and upper sashes intermediately hinged together, pivotal means supporting said upper sash within said frame, aligned pivotal vertically adjustable means supporting the lower sash within said frame, manually operable means engaging said lower sash pivotal means for effecting vertical adjustments thereof, and rotatable means vertically disposed and journaled within said frame operatively engaged by said lower sash pivotal means for vertical adjustments.

50 6. A window construction comprising a rectangular frame having a single sash guideway, aligned lower and upper sashes intermediately hinged together, pivotal means supporting said upper sash within said frame, aligned pivotal vertically adjustable means supporting the lower sash within said frame, manually operable means engaging said lower sash pivotal means for effecting vertical adjustments thereof, and manually releasable means supportingly engaging 55 said upper sash pivotal means.

7. A window construction comprising a rectangular frame having a single sash guideway, aligned lower and upper sashes intermediately hinged together, pivotal means supporting said upper sash within said frame, rotatable means vertically disposed and journaled within said frame, and pivotal vertically adjustable means supporting the lower end of said lower sash within said guideway and operably engaging said rotatable means for effecting adjustments thereof.

70 8. A window construction comprising a rectangular frame having a single sash guideway, rotatable means vertically disposed and journaled within said frame, aligned lower and upper sashes intermediately hinged together, pivotal means

supporting said upper sash within said frame, pivotal vertically adjustable means supporting the lower end of said lower sash within said guideway and operably engaging said rotatable means, and manually operable means engaging said rotatable means for effecting vertical adjustments of said lower sash, together with outward movements of its upper portion.

9. A window construction comprising a rectangular frame having a single sash guideway, 10 rotatable means vertically disposed and journaled within said frame, aligned lower and upper sashes intermediately hinged together, pivotal means supporting the upper end of said upper sash within said frame, pivotal vertically adjustable means supporting the lower end of said lower sash within said guideway and operably engaging said rotatable means, manually operable means engaging said rotatable means for effecting vertical adjustments of said lower sash, and manually releasable means supportingly engaging said upper sash pivotal means, said sashes opening outwardly at their hinged connection.

10. A window construction comprising a rectangular frame having a single sash guideway, 15 vertical hollow longitudinally slotted channel members provided within said frame, threaded rotatable means journaled within said channel members, aligned lower and upper sashes intermediately hinged together, pivotal means supporting the upper end of said upper sash adjustably and slidably provided within said channel members, pivotal vertically adjustable means supporting the lower end of said lower sash provided within said channel members and threadably engaging said rotatable means, and manually operable means for causing rotation of said rotatable means, effecting outward and vertical adjustments of said hinged connection.

11. A window construction comprising a rectangular frame, vertical hollow longitudinally slotted channel members provided within said frame, threaded rotatable means journaled within said channel members, a lower sash and an upper sash intermediately hinged together, pivotal means supporting said upper sash adjustably and slidably provided within said channel members, pivotal vertically adjustable means supporting said lower sash provided within said channel members and threadably engaging said rotatable means, manually operable means for causing rotation of said rotatable means, and weatherstripping between said sashes adapted to effect an initial outward movement of the sash hinged connection upon nominal movement of said manually operable means.

12. A window construction comprising a rectangular frame, a lower sash and an upper window sash intermediately hinged together, pivotal means supporting said upper sash within said frame, pivotal vertically adjustable means supporting the lower sash within said frame, manually operable means engaging said lower sash pivotal means for effecting vertical adjustments thereof, and weatherstripping between said sashes adapted to effect an initial outward movement of the sash hinged connection upon nominal movement of said manually operable means.

13. A window construction comprising a rectangular frame, a lower sash and an upper window sash intermediately hinged together, pivotal means supporting said upper sash within said frame, pivotal vertically adjustable means supporting the lower sash within said frame, manually operable means engaging said lower sash

5 pivotal means for effecting vertical adjustments thereof, and weatherstripping between said sashes and on the under side of said lower sash adapted when the sashes are closed to effect an initial outward movement of the sash hinged connection upon nominal movement of said manually operable means.

14. A window construction comprising a frame, vertical hollow longitudinally slotted channel members provided within said frame, threaded rotatable means journaled within said channel members, aligned lower and upper sashes intermediately hinged together, pivotal means supporting the upper end of said upper sash adjustably and slidably provided within said channel members, pivotal vertically adjustable means supporting the lower end of said lower sash provided within said channel members and threadably engaging said rotatable means, manually operable means for causing rotation of said rotatable means for effecting vertical and outward adjustments of said hinged connection, and manually releasable means supportingly engaging said upper sash pivotal means.

15. A window construction comprising a rectangular frame, vertical hollow longitudinally slotted channel members provided within said frame, threaded rotatable members having bevel gears on their lower ends journaled within said channel members, aligned lower and upper sashes intermediately hinged together, pivotal means supporting the upper end of said upper sash adjustably and slidably provided within said channel members, pivotal vertically adjustable means supporting the lower end of said lower sash provided within said channel members and threadably engaging said rotatable members, and a horizontal manually rotatable shaft with bevel gears on its ends in operative mesh with said 30 other bevel gears for causing rotation of said rotatable members, said hinged connection being adapted to vertical and outward adjustments.

16. A window construction comprising a rectangular frame having a single sash guideway, aligned lower and upper sashes intermediately hinged together, pivotal vertically adjustable means supporting the upper sash within said frame, aligned pivotal vertically adjustable means supporting the lower sash within said frame, and manually operable means engaging said lower sash pivotal means and said upper sash pivotal means for effecting vertical adjustments thereof.

17. A window construction comprising a rectangular frame, aligned lower and upper sashes intermediately hinged together, pivotal vertically adjustable means supporting the upper end of said upper sash within said frame, pivotal vertically adjustable means supporting the lower end of said lower sash within said frame, and manually rotatable threaded means threadably engaging both said upper and lower sash pivotal means for effecting vertical adjustment of said sashes, and outward movements of their hinged connection.

18. A window construction comprising a rectangular frame having a single sash guideway, aligned lower and upper sashes intermediately hinged together, pivotal vertically adjustable means supporting the upper sash within said frame, aligned pivotal vertically adjustable means supporting the lower sash within said frame, manually operable means engaging said lower sash pivotal means for effecting vertical adjustments thereof, and separate manually operable

means engaging said upper sash pivotal means for effecting vertical adjustments thereof.

19. A window construction comprising a rectangular frame, a lower and upper window sash intermediately hinged together, rotatable means vertically disposed and journaled within said frame, pivotal vertically adjustable means supporting said upper sash and operably engaging said rotatable means for effecting adjustments thereof, secondary rotatable means vertically disposed and journaled within said frame, and pivotal vertically adjustable means supporting the lower sash and operably engaging said secondary rotatable means for effecting adjustments thereof, said hinged connection being adapted to vertical and outward adjustments. 15

20. A window construction comprising a rectangular frame, a lower and upper window sash intermediately hinged together, a hollow threaded rotatable tube vertically disposed and journaled within said frame, pivotal vertically adjustable means supporting said lower sash and threadably engaging said tube for effecting adjustments of said means, a secondary rotatable threaded shaft vertically disposed within said tube and also journaled within said frame, and pivotal vertically adjustable means supporting the upper sash and threadably engaging said threaded shaft for effecting adjustments thereof.

RODNEY DAWES.
